INTERNAL COMBUSTION ENGINE

Filed April 2, 1926

Fig. 1.

UNITED STATES PATENT OFFICE.

OLAV ESKIL JORGENSEN, OF FOREST HILLS, NEW YORK, ASSIGNOR TO WORTHINGTON
PUMP AND MACHINERY CORPORATION, OF NEW YORK, N. Y., A CORPORATION OF
VIRGINIA.

INTERNAL-COMBUSTION ENGINE.

Application filed April 2, 1926. Serial No. 99,235.

This invention relates to internal combustion engines and more particularly to a double-acting two-cycle engine of the Diesel or oil-burning type.

5 The object of the present invention is to provide a double-acting two-cycle engine of relatively great horse-power in which lightness of weight and cost of manufacture per horse-power are materially reduced over similar approved types of engines of this character.

10 Relatively great weight and mass of metal have been heretofore required in the construction of double-acting two-cycle oil engines to 15 compensate for the stress and strain of operation of the engine and to permit distribution of such stress so as to obtain the maximum longevity of the engine, rendering high horse-power engines of this type impractical for 20 portable use except in marine work.

25 It is the object of the present invention to construct the engine frame, cylinder and passage or port block in such manner as to distribute the stresses of operation of the engine 30 from the cylinder to the engine frame and further to locate the passage or port block intermediate the ends of the cylinder and integral therewith, with a single scavenging port and a single exhaust port for the double-acting engine, all of which combine to 35 reduce the weight of the engine structure without weakening it.

40 With these objects in view, the invention consists in various features of construction 35 and combination of parts, which will be first described in connection with the accompanying drawing, showing a double-acting internal combustion engine of the preferred form embodying the invention, and the features 45 forming the invention will be specifically pointed out in the claims.

In the drawing—

Figure 1 is the vertical section through the engine structure.

45 Figure 2 is a cross section through the engine taken on the line 2—2 of Figure 1.

Referring to the drawing, the engine frame 1 has a relatively thick annular flange 2 on its upper end which is reinforced by suitable 50 webs 3.

The lower cylinder section 4 fits within the frame 1 and has the passage block 5 formed integrally therewith at the upper end of the lower cylinder section. The lower cylinder 55 section 4 has an extension 4^a formed thereon

which co-operates with the frame 1 in forming the cooling chamber 4^b. The passage block 5 has a relatively heavy annular upper portion 6, the upper surface of which is recessed and receives the relatively heavy flange 60 7 formed on the lower end of the upper cylinder section 8. A clamping collar or ring 9 fits over the flange 7, about a portion of the outer surface of the upper cylinder section 8 and about the lower edge of the cooling 65 jacket 10.

Bolts 11 are threaded into the flange 2, extend upwardly through suitable bosses 12 in the passage block 6, and through the clamping collar 9. Clamping nuts 13 are threaded 70 upon the upper ends of the bolts 11 and engage against the clamping collar 9 for connecting the upper cylinder section 8, the lower cylinder section 4 and frame 1, through the flange 2, thereby providing a substantial unitary structure arranged so that the stresses 75 on the upper cylinder section 8, during the operation of the engine, will be delivered through the bolts 11 to the frame 1 while stress on the lower section 4 of the cylinder, 80 during the operation of the engine will also be delivered through the flange 7, clamping collar 9 and bolts 11 to the frame 1.

The weight of the engine is also decreased 85 over approved structures now in use by providing the single passage block, formed integral with and spaced between the upper and lower ends of the cylinder structure and provided at one side of its transverse center with the plurality of ports 14 opening out into the 90 chamber 15 from the interior of the cylinder. The chamber 15 opens out into the exhaust manifold 16. The passage block 5 is also provided with a plurality of ports 17 which have communication with the scavenging manifold 95 18. The piston 19 is constructed in such manner as to permit proper opening of the ports 14 and 16 during the operation of the engine, such as, for instance, the cutting away of the lower portion of the piston as shown at 20 to 100 permit opening of the port 16 and the relatively short concave surfaces 21 and 22 on the upper and lower ends of the piston respectively to permit proper opening of the ports 14. The upper surface of the piston 19 inclines from the upper limit of the concave cut-away portion 22 across the piston top to permit opening of the ports 16.

Fuel is supplied to the cylinder through the fuel spray valves 24 and 25 positioned, 110

respectively, at the upper and lower ends of the cylinder. The spray valves 24 and 25 may be of any approved construction.

While in the foregoing specification the invention has been more particularly shown and described as embodied in a vertical single cylinder engine, it is to be understood that the invention is applicable to multiple cylinder engines, either horizontal, vertical or inclined engines, and the terms "upper" and "lower" referring to the cylinder sections are to be understood as including cylinder sections which are not above and below each other but farthest from and nearest to the crankshaft.

It will be understood that the invention is not to be limited to the specific construction or arrangement of parts shown but that these may be modified widely within the invention defined by the claims.

What I claim is:

1. In an internal combustion engine, a frame, a cylinder including an upper section and a lower section, a clamping collar, and stress bolts extending through said clamping collar and connecting said upper and lower cylinder sections and said frame to distribute operating strains from the cylinder to the frame.
2. In a double-acting internal combustion engine, a frame, a cylinder comprising upper and lower sections, a passage block formed upon the upper end of the lower cylinder section and provided with scavenging and exhaust ports, a clamping collar engaging said upper cylinder section and bolts extending through said clamping collar and passage block and connected to said frame.
3. In an internal combustion engine, a frame, having a flange thereon, a cylinder,

a passage block formed on said cylinder and provided with scavenging and exhaust ports, a clamping collar engaging said cylinder, and bolts extending through the clamping collar and threaded into said flange for connecting the cylinder to the frame to distribute operating strains to the frame.

4. In an internal combustion engine, a frame, a flange thereon, a cylinder comprising upper and lower sections, a clamping collar engaging said upper section, and bolts extending through said clamping collar and into said flange for connecting the cylinder sections to each other and to said frame.

5. In an internal combustion engine, a cylinder comprising upper and lower sections, a passage block formed upon said lower section, a flange upon the lower end of said upper section, and resting upon said passage block a clamping collar engaging said flange, a frame, and bolts extending through the said clamping collar and passage block and connected to said frame for connecting the upper and lower cylinder sections to the frame.

6. In an internal combustion engine, a cylinder comprising upper and lower sections, a passage block formed on said lower section, a flange on said upper section and resting upon said passage block, a clamping collar engaging said flange, a frame, and bolts extending through said clamping collar and passage block and connected to said frame for connecting the upper and lower cylinder sections to each other and to the frame, and an extension formed on said lower cylinder section and co-operating with said frame to provide a cooling chamber.

In testimony whereof I affix my signature.

OLAV ESKIL JORGENSEN.
